UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

DELIVERY MECHANISM FOR PRINTING-PRESSES.

1,306,682.

Specification of Letters Patent. Patented June 17, 1919.

Application filed December 11, 1917. Serial No. 206,590.

To all whom it may concern:

Be it known that I, HOWARD M. BARBER, a citizen of the United States, and resident of Stonington, in the county of New London and State of Connecticut, have invented 5 a new and useful Improvement in Delivery Mechanism for Printing-PresSES, of which the following is a specification.

The object of my invention is to provide 10 certain improvements in delivery mechanism for sheet feed rotary printing presses whereby wide sheets after they are printed, are slit lengthwise of their travel and are combined with slip sheets and delivered in 15 piles side by side to allow the several piles of alternating printed and slip sheets to be handled separately.

My invention more specifically comprises 20 means for feeding the printed sheets through a slitting device to a transfer carrier to be associated thereon with slip sheets fed thereto side by side from a suitable source, the transfer carrier serving to convey the pairs of associated printed and slip 25 sheets to the delivery device.

A practical embodiment of my invention is represented in the accompanying drawings in which;

Figure 1 is a detail vertical section taken 30 from front to rear through a sheet feed rotary printing press and its delivery mechanism, embodying my invention.

Fig. 2 is a detail horizontal section through the press.

Fig. 3 is a detail vertical section at the 35 outer end of the endless delivery carrier, and

Fig. 4 is a detail horizontal section taken in the plane of the line IV—IV of Fig. 3.

The impression cylinder is denoted by 1, 40 its plate cylinders by 2, and the cylinder which feeds the sheets from the table 3 to the impression cylinder 1, by 3*.

The sheet delivery mechanism for the printing press includes the rotary printed 45 sheet feed carrier 4, mounted on a suitable shaft 5 and provided with a set of grippers 6, which grippers are arranged to take the head of the printed sheet from the impression cylinder 1 with the freshly printed 50 side of the sheet toward the cylinder 4. The printed sheet is slit lengthwise of its travel on the cylinder 4, into two or more smaller sheets, in the present instance into two smaller sheets, by a slitting disk 7 carried 55 by an arm 8 on a cross bar 9. A rotary slip

sheet feed carrier 10 is mounted on a shaft 11, and is provided with grippers 12 which are operated to take the slip sheets side by side from the feed table 13. A rotary transfer carrier 14 is mounted on a shaft 15, and 60 it is provided with one or more sets of grippers 16, in the present instance two sets are shown, which grippers are arranged to associate the slip sheets with their respective printed sheets, by first being raised to clear 65 the leading edges of the slip sheets and then remaining open until they reach the transfer point between the cylinders 4 and 14, where they seize the pairs of associated printed and slip sheets. The slip sheets are 70 under the control of the tapes 10* around the cylinder 10, which tapes coact with the cylinder 14 from the time the slip sheets are released by the grippers 12 until they are taken by the grippers 16. An endless de- 75 liverly carrier 17 is shown as provided at intervals with grippers 18 arranged to take the pairs of associated printed and slip sheets from the grippers 16 of the rotary transfer carrier 14, and to deliver the so as- 80 sociated pairs of printed and slip sheets in piles side by side on the delivery table 19.

The cams for controlling the operation of the grippers 6 on the rotary carrier 4, are denoted by 20, 21. The cams for controlling 85 the operation of the grippers 12 on the rotary carrier 10, are denoted by 22, 23. The cams for controlling the operation of the grippers 16 of the rotary carrier 14, are denoted by 24, 25. The cams for controlling 90 the operation of the grippers 18 on the endless delivery carrier 17, are denoted by 26, 27. Series of friction rollers 28, carried by spring-actuated rock levers 29 pivoted to arms 30 on the cross bar 9, 95 maintain control of the printed sheets on the rotary carrier 4, after the advance edges of the sheets have been released by the grippers 6.

Suitable sheet stops 31 are provided at the 100 delivery table 19, against which stops the leading edges of the associated printed and slip sheets are directed as they are released from the grippers 18 of the endless delivery carrier.

It is intended that the driving connections between the several parts may be arranged to drive the parts at the proper relative speeds, and as such driving mechanism may be of any well known or approved form, no 110

specific description of the same will be given herein.

It is evident that various changes may be resorted to in the form, construction and arrangement of the several parts without departing from the spirit and scope of my invention, and hence I do not intend to limit myself to the structure herein described, but

What I claim is:

- 10 1. A printed sheet delivery mechanism including a common means for feeding printed sheets side by side, a common means for feeding slip sheets side by side, a common means for associating the slip sheets with their respective printed sheets and a common means for delivering the pairs of so associated sheets.
- 15 2. A printed sheet delivery mechanism including a common means for feeding printed sheets side by side, a common means for feeding slip sheets side by side, a common means for associating the slip sheets with their respective printed sheets and a common means for delivering the pairs of so associated sheets in piles side by side.
- 20 3. A printed sheet delivery mechanism including a rotary carrier for feeding printed sheets side by side, a common means for feeding slip sheets side by side, a common means for associating the slip sheets with their respective printed sheets and a common means for delivering the pairs of so associated sheets in piles side by side.
- 25 4. A printed sheet delivery mechanism including a rotary carrier for feeding printed sheets side by side, a common means for feeding slip sheets side by side, a common means for associating the slip sheets with their respective printed sheets and a common means for delivering the pairs of so associated sheets in piles side by side.
- 30 5. A printed sheet delivery mechanism including a rotary carrier for feeding printed sheets side by side, a common means for feeding slip sheets side by side, a common means for associating the slip sheets with their respective printed sheets and a common means for delivering the pairs of so associated sheets.
- 35 6. A printed sheet delivery mechanism including a rotary carrier for feeding printed sheets side by side, a common means for feeding slip sheets side by side, a common means for associating the slip sheets with their respective printed sheets and a common means for delivering the pairs of so associated sheets in piles side by side.
- 40 7. A printed sheet delivery mechanism including a rotary carrier for feeding printed sheets side by side, a common means for feeding slip sheets side by side, a common means for associating the slip sheets with their respective printed sheets and a common means for delivering the pairs of so associated sheets.
- 45 8. A printed sheet delivery mechanism including a rotary carrier for feeding printed sheets side by side, a common means for feeding slip sheets side by side, a common means for associating the slip sheets with their respective printed sheets and a common means for delivering the pairs of so associated sheets in piles side by side.
- 50 9. A printed sheet delivery mechanism including a common means for feeding printed sheets side by side, a common means for feeding slip sheets side by side, a rotary carrier for associating the slip sheets with their respective printed sheets and a common means for delivering the pairs of so associated sheets.
- 55 10. A printed sheet delivery mechanism including a common means for feeding printed sheets side by side, a common means for feeding slip sheets side by side, a rotary carrier for associating the slip sheets with their respective printed sheets and a common means for delivering the pairs of so associated sheets in piles side by side.
- 60 11. A printed sheet delivery mechanism including a common means for feeding printed sheets side by side, a rotary carrier for feeding slip sheets side by side, a rotary carrier for associating the slip sheets with their respective printed sheets and a common means for delivering the pairs of so associated sheets.
- 65 12. A printed sheet delivery mechanism including a common means for feeding printed sheets side by side, a rotary carrier for feeding slip sheets side by side, a rotary carrier for associating the slip sheets with their respective printed sheets and a common means for delivering the pairs of so associated sheets in piles side by side.
- 70 13. A printed sheet delivery mechanism including a rotary carrier for feeding printed sheets side by side, a common means for feeding slip sheets side by side, a rotary carrier for associating the slip sheets with their respective printed sheets and a common means for delivering the pairs of so associated sheets.
- 75 14. A printed sheet delivery mechanism including a rotary carrier for feeding printed sheets side by side, a common means for feeding slip sheets side by side, a rotary carrier for associating the slip sheets with their respective printed sheets and a common means for delivering the pairs of so associated sheets in piles side by side.
- 80 15. A printed sheet delivery mechanism including a common means for feeding printed sheets side by side, a common means for feeding slip sheets side by side, a delivery device and a rotary transfer carrier arranged to take the slip sheets, associate them with their respective printed sheets and transfer the so associated sheets to the delivery device.

16. A printed sheet delivery mechanism including a common means for feeding the printed sheets side by side, a common means for feeding the slip sheets side by side, a 5 delivery device and a rotary transfer carrier arranged to take the slip sheets, associate them with their respective printed sheets and transfer the so associated sheets to the delivery device, said delivery device 10 being arranged to deliver the pairs of associated sheets in piles side by side.

17. A sheet delivery mechanism for printing presses including means for feeding the printed sheets and slitting them lengthwise 15 of their travel, a common means for feeding slip sheets side by side into association with their respective printed sheets and a common means for delivering the pairs of so associated printed and slip sheets.

20 18. A sheet delivery mechanism for printing presses including means for feeding the printed sheets and slitting them lengthwise of their travel, a common means for feeding slip sheets side by side into association 25 with their respective printed sheets and a common means for delivering the pairs of so associated printed and slip sheets in piles side by side.

25 19. A sheet delivery mechanism for printing presses including a printed sheet feeding cylinder, means for slitting the printed sheets thereon lengthwise of their travel, means for feeding slip sheets side by side 30 into association with their respective printed sheets and means for delivering the pairs of so associated printed and slip sheets.

35 20. A sheet delivery mechanism for printing presses including a printed sheet feeding cylinder, means for slitting the printed sheets thereon lengthwise of their travel, 40 means for feeding slip sheets side by side into association with their respective printed sheets and means for delivering the pairs of so associated printed and slip sheets in piles 45 side by side.

45 21. A sheet delivery mechanism for printing presses including means for feeding the printed sheets and slitting them lengthwise of their travel, a rotary transfer carrier, 50 means for feeding slip sheets side by side thereto, to be associated with their respective printed sheets and means for delivering the pairs of so associated printed and slip sheets.

55 22. A sheet delivery mechanism for print-

ing presses including means for feeding the printed sheets and slitting them lengthwise of their travel, a rotary transfer carrier, means for feeding slip sheets side by side thereon, to be associated with their respective 60 printed sheets and means for delivering the pairs of so associated printed and slip sheets in piles side by side.

23. A sheet delivery mechanism for printing presses including a rotary printed sheet 65 feeding carrier, means for slitting the printed sheets thereon lengthwise of their travel, a rotary transfer carrier, means for feeding slip sheets side by side thereto, to be associated with their respective printed sheets 70 and means for delivering the pairs of so associated printed and slip sheets.

24. A sheet delivery mechanism for printing presses including a rotary printed sheet 75 feeding carrier, means for slitting the printed sheets thereon lengthwise of their travel, a rotary transfer carrier, means for feeding slip sheets side by side thereto, to be associated with their respective printed sheets and means for delivering the pairs of so 80 associated printed and slip sheets in piles side by side.

25. A sheet delivery mechanism for printing presses including a rotary printed sheet 85 feeding carrier, means for slitting the printed sheets thereon lengthwise of their travel, a delivery device, means for feeding slip sheets side by side and a rotary transfer carrier arranged to take the slip sheets side by 90 side, associate them with their respective printed sheets and transfer the pairs of so associated printed and slip sheets to a delivery device.

26. A sheet delivery mechanism for printing presses including a rotary printed sheet 95 feeding carrier, means for slitting the printed sheets thereon lengthwise of their travel, a delivery device, means for feeding slip sheets side by side and a rotary transfer carrier arranged to take the slip sheets side by 100 side, associate them with their respective printed sheets and transfer the pairs of so associated printed and slip sheets to the delivery device, said delivery device being arranged to deliver the pairs of sheets in 105 piles side by side.

In testimony that I claim the foregoing as my invention I have signed my name this seventh day of December, 1917.

HOWARD M. BARBER.
